[57] CLAIM

The ornamental design for a desk carrel, as shown and described.

DESCRIPTION

FIG. 1 is a top plan view of a desk carrel showing our design;

FIG. 2 is a front elevational view;

FIG. 3 is a rear elevational view; and

FIG. 4 is a left side elevational view thereof.

FIG. 5 is a top plan view of a second embodiment of a desk carrel showing our design;

FIG. 6 is a front elevational view; and

FIG. 7 is a rear elevational view thereof.

FIG. 8 is a top plan view of a third embodiment of a desk carrel showing our design; and

FIG. 9 is a side elevational view thereof.

FIG. 10 is a front perspective view of the desk carrel shown in FIG. 1.
